US0D1070335S

(12) **United States Design Patent** (10) **Patent No.:** **US D1,070,335 S**
(45) **Date of Patent:** **** Apr. 15, 2025**

(54) **CONTAINER**

(71) Applicant: **Sanner Pharmaceutical & Medical Packaging Materials (Kunshan) Co. Ltd., Kunshan (CN)**

(72) Inventor: **Hongbao Wang, Suzhou (CN)**

(73) Assignee: **SANNER PHARMACEUTICAL & MEDICAL PACKAGING MATERIALS (KUNSHAN) CO. LTD (CN)**

(**) Term: **15 Years**

(21) Appl. No.: **29/839,244**

(22) Filed: **May 19, 2022**

(30) **Foreign Application Priority Data**

Nov. 22, 2021 (CN) 202130766674.3
(51) **LOC (15) Cl.** **03-01**
(52) **U.S. Cl.**
USPC **D3/203.2**

Assistant Examiner — Caitlin A Laverty

(74) *Attorney, Agent, or Firm* — Sheridan Ross P.C.

(57) **CLAIM**

The ornamental design for a container as shown and described.

DESCRIPTION

FIG. 1 is a perspective view of the container;
FIG. 2 is a top view thereof;

FIG. 3 is a bottom view thereof;

FIG. 4 is a front view thereof;

FIG. 5 is a back view thereof;

FIG. 6 is a left side view thereof;

FIG. 7 is a right side view thereof; and,

FIG. 8 is a right side open view thereof.

The broken lines in the drawing represent portions of the container that form no part of the claimed design.

1 Claim, 8 Drawing Sheets
